UNITED STATES PATENT OFFICE.

ERNST STORCH, OF BERLIN, GERMANY.

VACUUM DRYING APPARATUS.

SPECIFICATION forming part of Letters Patent No. 683,189, dated September 24, 1901.

Application filed October 24, 1898. Renewed July 15, 1901. Serial No. 68,439. (No model.)

To all whom it may concern:

Be it known that I, ERNST STORCH, a citizen of the Empire of Germany, residing at Berlin, Germany, have invented certain new and useful Improvements in Vacuum Drying Apparatus, of which the following is a specification.

My invention relates to a novel construction of vacuum drying apparatus, the object being to provide an apparatus of this kind in which a plurality of heaters are employed, such heaters or trays at the same time allowing of dispensing with the usual braces employed for strengthening the walls of the apparatus, and, further, so arranging said trays as to permit a quick outflow of the air and the vapors both at the top and the bottom of the apparatus; and the invention consists in the features of construction and combination of parts hereinafter fully described and claimed.

In order that this my invention may be the more readily and properly understood and carried into practical effect, I have shown one embodiment of same in the accompanying illustrative drawings, in which—

Figure 1 is a vertical sectional view of my improved apparatus. Fig. 2 is a plan sectional view of same.

Referring to the drawings, in which like letters refer to like parts throughout the figures, A designates the main casing of my improved vacuum drying apparatus, said casing being of any shape and suitable dimensions. Within this casing is a plurality of closed trays or boxes H, horizontally arranged one above the other at suitable points and resting on brackets h, secured to casing A. The heating medium or fluid is led to said trays or boxes through pipe B and therefrom through pipe C.

The apparatus is closed in an absolute airtight manner at i by a door or several doors T.

The casing A is provided with a top outflow-opening E and a bottom outflow-opening F for the air and gases which are to be expelled from the drying apparatus. Said openings are provided with pipes E' and F', respectively, leading to a suitable air-pump, condenser, or any sucking device or machine capable of producing high vacuum within the apparatus.

The pipes E' and F' may extend from the drying apparatus in any preferred manner;

but I preferably join said pipes together, as shown in the drawings, in turning pipe F' upward to pipe E'. In this case to facilitate 55 the flow of the gases through said pipe F', I heat the same in any suitable manner. For this purpose I may provide an inner pipe R of smaller diameter or an outer jacket R', said pipe R and jacket R' receiving the heating medium at o, said medium or fluid being led therefrom at o'.

I preferably provide nozzle-like pipes D leading from opening E and being arranged within the suction-pipe E', thereby tending 65 to produce more or less of an aspirating effect in the drawing off of the vapors from the apparatus.

A very high pressure being produced on the walls of an apparatus of this kind, (nearly 70 one kilogram per square centimeter,) said walls were heretofore strongly braced to withstand the strain to which they were subjected. Such bracing is very objectionable in a great many particulars, among which I state the 75 following: First, said bracing increases the weight of the apparatus and makes its manufacture a very expensive one; second, inner strengthening-ribs hinder the quick flow of 80 the evolved gases to the condenser, whereby 80 the drying action of the apparatus will be disadvantageously influenced, and, third, if such bracing is employed the dimensions of the apparatus are limited, since for larger apparatuses said bracing would be excessive and 85 irrational. These and many other objections are overcome with the apparatus herein described by the use of heating trays or boxes 90 H, forming very strong tubular trusses and adapted and constructed to strengthen the walls of the apparatus and to relieve said walls from the pressure produced thereon. For this purpose said trays or boxes are supported at determinate points P, against which the walls of the apparatus are pressed, and 95 said supporting-points may be suitably determined, so that I may employ comparatively thin walls of sheet-iron. Furthermore, with the usual apparatuses the air and gases can only be drawn out at the uppermost point 100 thereof; but a great deal of the vapors within such apparatus travel downward on account of their gravity, and these vapors must be heated again to a sufficient degree to rise

to top of the apparatus and flow through the outlet there provided.

As hereinbefore described, my improved apparatus has two outlets, an upper and a lower one, so as to allow of the air-pump, condenser, and the like drawing out the air and gas both at the top and at the bottom of the apparatus.

Having fully described my invention, what I claim, and desire to secure by Letters Patent, is—

In a vacuum drying apparatus, the combination

with a casing, of a vapor-outlet pipe having branches leading from the upper and lower parts of the casing that from the lower part leading upward and joining the other 15 branch, and means for heating the said upwardly-extending pipe.

ERNST STORCH.
